PNEUMATICALLY OPERATED PICKER
MECHANISM FOR LOOMS

Charles G. Scott, Kingsport, Tenn.

Application December 11, 1950, Serial No. 200,147

7 Claims. (CL 139—144)

1

This invention comprises novel and useful improvements in a pneumatically operated picker mechanism for looms and more specifically pertains to an air pressure operated mechanism capable of imparting a controlled and adjustable stroke to the picker stick of looms in synchronization with the operation of the loom.

The primary object of this invention is to provide an air pressure operated mechanism for actuating the loom picker stick in properly timed relation to the motion of the loom.

A further object of the invention is to provide a device in conformity with the preceding object in which the stroke of the same shall be capable of adjustment and of variations in timing as required.

Yet another object of the invention is to provide an air pressure operating means as set forth in the foregoing objects in which the moving parts shall have a more efficient cooperation with each other to the end that a more serviceable and dependable mechanism is provided and one which shall have a longer life in operation.

These, together with various ancillary features and objects of the invention, which will later become apparent as the following description proceeds, are attained by the present invention, a preferred embodiment of which has been illustrated, by way of example only, in the accompanying drawings, wherein:

Figure 1 is a side elevational view of the air pressure operating means of a picker stick in accordance with the present invention, the mechanism being shown in the position when the air pressure supply valve is open and the device is ready to actuate a picker stick from its normal rest position;

Figure 2 is an end elevational view of the mechanism shown in Figure 1 being taken from the right end thereof;

Figure 3 is a view taken in end elevation from the left end of the view of the device as shown in Figure 1;

Figure 4 is an end elevational view taken upon an enlarged scale, substantially upon the plane indicated by the broken section line 4—4 of Figure 1 and showing in particular the construction of the latch mechanism of the invention;

Figure 5 is a view taken substantially upon the plane indicated by the section line 5—5 of Figure 2 and showing in vertical central section the position of the parts when the device is in the position of Figure 1;

Figure 6 is a side elevational view of a portion of the mechanism and showing in particular a

2

part of the latch operating mechanism and of the carriage forming part of the invention;

Figure 7 is a view similar to Figure 5 but showing the position of the parts at the other end of the stroke, the exhaust valve being open and the intake valve closed; and,

Figures 8 and 9 are vertical transverse sectional views taken substantially from the plane indicated by the section lines 8—8 and 9—9 respectively of Figure 7, these views being taken in the directions indicated by the arrows.

Referring now more specifically to the accompanying drawings, wherein like numerals designate similar parts throughout the various views, it will be seen that the picker operating mechanism forming the subject of this invention includes an air pressure operated cylinder and piston assembly which is adapted to be mounted upon a portion of the frame of a loom and is operatively connected with a power shaft of the loom whereby the mechanism is operated in timed relation to the motion of the loom, and is further operatively connected with a picker stick forming a part of a picker stick mechanism of a loom.

The principles of this invention and the embodiment illustrated are obviously capable of operation with conventional forms of looms, the operating mechanism of the same, and in particular with the picker stick mechanism thereof.

As is well known, it is necessary to impart a periodic, or fully timed, reciprocatory motion transverse of the loom to a picker stick during the operation of the loom. Heretofore, various mechanical linkages have been employed to effect the desired operation of the picker stick. It has also been heretofore proposed to employ air pressure for giving the desired motion. However, such means have not been heretofore entirely satisfactory since it has been difficult to accurately and properly time the actuation of the picker stick by the air pressure operating means; as well as to vary the amplitude of movement of the operating means and to control the same in a synchronized and automatic manner.

The fundamental purpose of the present invention is to provide an air pressure operated mechanism whose timing, amplitude of stroke and position of stroke may be accurately and precisely adjusted and controlled and automatically effected from the rotation of any conventional rotating shaft of a loom from which power may be obtained in proper synchronization with the motion of the loom.

In the accompanying drawings, it will be seen that there has been provided an air pressure

operated cylinder 10 having a cylinder head 12 closing one end of the same, the other end of the cylinder being open and being provided with internal screw threads 14 for receiving an externally screw-threaded plug 16 which is centrally apertured to constitute a guide for slidably receiving and guiding the piston rod 18 forming a part of an air pressure operated piston 20 which is slidably received and retained within the cylinder 10.

At its outer end, the piston rod 18 is externally threaded as at 22 and has adjustably secured thereon as by adjusting nuts 24 and 26, a carriage indicated generally by the numeral 28 and which has removably secured thereto as by fastening bolts 30, a laterally extending lug 32 adapted to abut and impart oscillation to a picker stick of any conventional form, not shown. In order to understand the purposes, construction and operation of the present invention, it is merely necessary to understand that the carriage 28 which is reciprocated by movement of the piston 20, imparts its rectilinear, reciprocatory motion to a picker stick a portion of which is shown at 32.

At any convenient portion along its length, the cylinder 10 is provided with a passage 34 having a port 36 opening into the interior of the cylinder, the port 36 being so placed as to vent the interior of the cylinder between the adjacent surfaces of the plug 16 and the piston 20 in order to avoid a dashpot effect during the reciprocation of the piston.

Referring now more particularly to the construction and mounting of the carriage 28, especial attention is invited to the showing in Figures 6 and 8. Here it will be seen that the carriage consists of a yoke or U-shaped member having a pair of arms 38 and 40 which are integrally connected at one end by a vertically disposed web portion or bar 42, the upper arm 38 being preferably longer than the lower arm 40 for a purpose which will be later set forth. These arms are adapted to slidably embrace the opposite sides of the cylinder 10 for relative sliding and guided movement thereon. For that purpose, as shown more clearly in Figures 7 and 8, the cylinder 10 whose perimeter may be a square as shown in Figure 8, is provided on a pair of opposite sides, such as the upper and lower surfaces of the same, with a pair of dove-tail shaped longitudinally extending guide channels 44 and 46. The upper and lower arms 38 and 40 are provided with correspondingly shaped depending longitudinally extending ribs 48 and 50 constituting keys or retaining means which are slidably received and retained within the channels 44 and 46, and which may be inserted from the open right hand end of these guide channels as suggested in Figure 7. The channel and key arrangement prevents relative rotation between the carriage and the cylinder.

As shown more clearly in Figures 5, 6 and 7, the lower yoke arm 40 of the carrier is provided at its outer end with a thickened portion 52 from which forwardly extends an adjusting bolt 54 adjustably attached thereto as by a lock nut 56. The adjusting bolt 54 constitutes an adjustable operating means or actuator for the inlet valve mechanism to be hereinafter described. The end of the other arm 38 in itself constitutes an abutment surface or operating means for the pressure exhaust valve operating mechanism as set forth hereinafter.

Referring now to Figures 2 and 3, it will be apparent that the air pressure operated cylinder

and piston may be detachably secured to a portion of the frame of the loom, the frame being indicated at 58, by suitable fastening bolts or the like 60.

5 A latch means is provided for retaining the air pressure operated piston and the carriage attached thereto at the inner end or inoperative position of their stroke and releasing the same for air pressure operation in timed relation to the 10 operation or motion of the loom. This latch means, and its operating mechanism, shown best in Figures 4 and 6, consists of an actuator or latch bar in the form of a yoke 62 having a pair of latching arms 64 and an arcuate midportion 66. The latch arms are reciprocable in chambers 70 15 suitably formed in housings 72 carried by the side of the cylinder 10 and are provided within the chambers 70 with collars or shoulders 68. A compression spring 74 is seated in each of the chambers 70 and surrounds the latch arm 64, to engage 20 one end of the chamber and the collar or shoulder 68 to thereby yieldingly urge the latch bars and the entire yoke into the latching position, whereby, as shown in Figures 2 and 4, the ends of the latch bars are disposed across and in the path of travel of the carriage yoke, web or cross bar 42.

It will now be apparent that the springs normally urge the latch bars into latching position until the yoke is positively withdrawn by a power operated means to be subsequently described. The outer sides of the ends of the latch bars may be provided with beveled camming surfaces 76 whereby the inward travel of the web portion 42 of the carriage yoke, on striking the camming surfaces, will momentarily move the latch bars laterally to permit the carriage to move past them and to reach its innermost position, after which the spring-urged latch will retain the carriage in its inward position until positively released as set forth hereinafter.

40 Journalled in suitable brackets along the side of the cylinder 10, one such bracket being shown at 78, is a rotatable latch shaft 80 having a beveled gear 82 at one end which meshes with a beveled gear 84 carried by a lay shaft 86 which 45 is adapted to connect, in any desired manner not shown, with one of the rotating shafts of the loom to operate the latching shaft 80 in synchronization with motion of the loom. The latching shaft 80 extends within the yoke 62 and adjacent the arcuate portion 66 at the middle thereof, as shown more clearly in Figure 4, and is provided with an operating cam 88.

It will now be apparent from Figures 4 and 6 55 that the shaft 80 will be operating in timed relation to the operation of the loom, and by the cam 88, the latch will be withdrawn in proper synchronization with the loom motion to release the air pressure operated cylinder, piston and carriage for properly timed operation of the picker stick.

60 Attention is now directed more specifically to Figures 5 and 7 for an understanding of the construction and operation of the air pressure supply and exhaust means for the air pressure operated cylinder 10, and the control mechanism therefor.

Adjacent the cylinder head 12, a side wall of the cylinder is provided with an air pressure inlet port or passage 90 which communicates with a registering passage 92 extending through a valve housing 94 having a cover plate 96 and which is removably attached to the cylinder as by fastening bolt or the like 98. A flat, plate valve 100 is slidably received in the valve hous-

ing 94 and in turn is provided with a valve port 102 which is adapted to register during reciprocation of the valve, with a passage 92 in the valve housing and with an inlet passage 104 extending through the valve housing cover plate 96 and communicating with an air pressure supply conduit 106 connected with any suitable and conventional source of air supply, not shown.

It will be seen from Figures 5 and 7 that the passages 90, 92, 104 and the conduit 106 are aligned with each other so that once during each reciprocation of the valve 100, the valve passage 102 will establish communication from the interior of the cylinder 10 to the source of air supply.

The valve 100 is provided at one end with a valve stem 108 which is encircled by a compression spring 110 and whose opposite ends abut shoulders on the valve plate 100 and a spring seating plate 112 secured to the cylinder head as by fastening screws 114. It will thus be seen the valve is spring urged, as shown in Figure 7, to its closed position but may be opened by being moved against the resistance of its spring until the passage 102 aligns with the other passages above mentioned. To operate the air supply valve 100 in adjustable and properly timed relation to the position and movement of the carriage 28 and a picker stick actuated thereby, one end of the valve 100 is exposed beyond the end of the valve housing 94 into the path of travel of the operating and adjusting screw 54. It will now be seen, that when the carriage is at its inward position, as shown in Figure 5, the actuating and adjusting screw 54 will abut the end of the valve 100, and urge the latter to its open position as shown in Figure 5. Obviously, by properly adjusting the screw 54, the precise time at which the air supply valve 100 can be opened and closed may be accurately regulated and adjusted. It will be further appreciated that the proper adjustment of the piston rod 18 upon the yoke web 42 by the adjusting nuts 24 and 26, will further facilitate the adjustment of the piston position relative to the operation of the valve.

The air pressure exhaust valve comprises a poppet valve 116 adapted to cooperate with a conical valve seat 118 formed in the inner surface of the cylinder head 12, this valve being provided with a valve stem 120 extending through the cylinder head and being surrounded by a compression spring 122 which normally urges the valve to its closed position. The valve controls suitable exhaust passages 124 formed at the cylinder head 12 and communicating with the valve seat 118 as shown.

As just mentioned, the spring 122 normally yieldingly urges the valve 116 into its closed position. However, a valve actuator is operatively associated with the exhaust valve, this actuator conveniently comprises a rocker 126 having an intermediate arcuate portion 128 and an extremity 130 which is adapted to abut the end of the valve stem 120 for operating the same. The other end of the rocker 126 is secured as by fastening bolts or the like 132 to a block 134 pivotally mounted as at 136 between a pair of mounting brackets 138 carried by the side of the cylinder 10. An adjusting screw 140 is screw-threadedly engaged in the block 134 and locked in adjusted position therein as by a lock-nut 142. The adjusting screw 140 is disposed in the path of travel of the end of the arm 38, whereby the screw, the block 134 and the rocker 126 may be oscillated about the pivot 136 to re-

move the rocker from engagement with the valve stem. A tension spring 144 has its opposite ends connected to the cylinder head 12 and to the looped or middle portion 128 of the rocker arm 126 to yieldingly urge the rocker towards the cylinder head, and to normally yieldingly override the spring 122, the spring 144 being of greater strength than spring 122, whereby the valve will be normally maintained in open position by the actuator.

From the foregoing, it will now be apparent that with the piston, the carrier and the arm 38 displaced from their inward position, the arm 38 will be out of contact with the adjusting screw 140, at which time the spring 144 and the rocker arm 126 will override the spring 122 and maintain the exhaust valve in its open position. When, however, the piston, the carrier and the arm 38 have moved a predetermined distance toward their inward position, the actuator rocker at 130 will be removed from contact with the valve stem, whereupon the spring 122 will be permitted and will be effective to close the valve 116. Obviously, adjustment of the screw 140 will regulate the time at which and during which the exhaust valve is opened and closed.

From the foregoing, it will be apparent that the air pressure supply to the cylinder and the air pressure exhaust therefrom may be accurately adjusted and regulated in reference to the time and extent of the piston, and consequently of the carrier secured to the piston and the picker stick mechanism of the stick connected with the carrier.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

Having described the invention, what is claimed as new is:

1. A picker mechanism for looms comprising a fluid pressure cylinder having a piston slidable therein, a carriage connected to said piston for movement therewith, means connected to said carriage for actuating a loom picker upon reciprocation of said carriage, fluid pressure supply means and fluid pressure exhaust means for said cylinder, a valve controlling said supply means, and operating means for said valve responsive to movement of said carriage a predetermined distance in one direction.

2. The combination of claim 1 in which said valve operating means is carried by the carriage.

3. The combination of claim 1 in which said carriage is slidable about said cylinder and said mechanism includes means preventing relative rotation of said carriage and cylinder.

4. A picker mechanism for looms comprising a fluid pressure cylinder having a piston slidable therein, a carriage connected to said piston for movement therewith, means on said carriage for actuating a loom picker upon reciprocation of said carriage, fluid pressure supply means and fluid pressure exhaust means for said cylinder, a valve controlling said supply means, operating means for said valve operable in timed relation to movement of said carriage, said fluid pressure exhaust means comprising an exhaust valve, means resiliently urging said exhaust valve to

closed position, a valve actuator yieldingly urged to normally override said resilient means and maintain said exhaust valve open, and means operative upon movement of said carriage a predetermined distance in one direction to render said valve actuator inoperative, whereby said resilient means is effective to close said valve.

5. A picker mechanism for looms comprising a fluid pressure cylinder having a piston slidable therein, a carriage connected to said piston for movement therewith, means on said carriage for actuating a loom picker upon reciprocation of said carriage, fluid pressure supply means and fluid pressure exhaust means for said cylinder, a valve controlling said supply means, operating means for said valve operable in timed relation to movement of said carriage, said valve being spring urged to its closed position, and means operative upon movement of said carriage a predetermined distance in one direction for moving 10 said valve to its open position.

6. The combination of claim 1, including a

latch for retaining said carriage at one end of its path of travel, and operating means for said latch operable in timed relation and by a power shaft of a loom.

5. The combination of claim 1, wherein said carriage is slidable about said cylinder, said cylinder has external longitudinally-extending guides, and said carriage is slidably retained upon said guides.

CHARLES G. SCOTT.
